[57] CLAIM

The ornamental design for a beach mat, as shown and described.

DESCRIPTION

FIG. 1 is a front elevational view of the beach mat according to my new design in a rolled-up condition;

FIG. 2 is a right-hand side elevational view thereof; a left-hand side view is similar to the view of FIG. 2;

FIG. 3 is a top plan view thereof;

FIG. 4 is a bottom plan view thereof;

FIG. 5 is a rear elevational view thereof;

FIG. 6 is a top, left-corner perspective view of the beach mat of my invention in an unrolled condition;

FIG. 7 is a rear elevational view thereof; and,

FIG. 8 is a bottom, right-corner perspective view of the beach mat in the unrolled position.
